UNITED STATES PATENT OFFICE.

EDDIE ORANGE HIGDON, OF LOS ANGELES, CALIFORNIA.

HOLDING FRAME.

Application filed May 10, 1923. Serial No. 633,030.

My invention is an improved holding frame, particularly applicable for holding maps, guide data, dates, etc. in a readable position on the steering post of an automobile.

The object of my invention is to provide a frame, which may be readily clamped to the steering column under the wheel, and the angle of the frame may be easily adjusted to suit the convenience of the user.

Another object is to provide a means to illuminate the frame when used at night.

In the annexed drawing in which my invention is illustrated I have shown the preferred form of my invention but it may be embodied in other forms, and in this application I wish to cover my invention in whatever form it may be embodied.

Figure 1 is a side view of my holder frame.

Figure 2 is a transverse sectional view of the same.

Referring more particularly to the drawing: the frame 1 is mounted on the steering column 2, by means of a clamp 3, which encircles said column. The holding frame 1 consists of a base plate 4, to which a blade 5 is secured. This blade is pivoted at 6 to the clamp 3, and a bolt 7 extends through said clamp and through a slot 8 in the blade 5. The blade, and base plate 4, may thus be adjusted with relation to the clamp 3. To further secure the blade 5 in position a screw 9 extends through a slot 10 in the clamp 3 and into the lower edge of the blade.

The frame back 11 is pivoted to the base 4 by hinges 12. Adjusting brackets 13 are pivoted to the back 11, and set screws 14 are mounted in the base 4 and extend into slots 15 in said brackets. Thus by loosening the screws 14 the back 11 may be set at any desired angle with the base 4.

A cover panel 16 is hinged at its rear edge to the back 11, and its forward edge is screwed to the back by screws 17. A glass plate 18 is secured to the panel 16 under which the map may be seen.

The maps or notes are inserted under the glass 18 by loosening the screws 17 and raising the panel 16; after the map is in position the screws are tightened which holds the map securely in position.

In order that the map may be visible at night a reflector 19 is secured to the panel 16, and a light 20 is positioned therein. The

light 20 screws into a socket 21 on the reflector 19.

A switch plug (not shown) is slipped on to the terminal 22, and a lead 23 extends under the back 11 from the terminal to a contact block 24 near the forward edge of the back. A yieldable contact pin 25 is mounted in a block 26 on the panel 16, a spring 27 back of said pin urges it downward into contact with the block 24. A lead 28 extends from the pin 25 to the light 20. The object of the yieldable pin is to compensate for various thicknesses of maps between the panel 16 and back 11. The pin will always be forced downwardly far enough to form contact with the block 24.

Having described my invention I claim:

1. A holding frame comprising a base plate, a clamp, means to pivot said plate to said clamp, a back mounted on said base plate and a cover panel mounted on said back, a reflector mounted on said cover panel, and a light mounted in said reflector, an electrical contact block in said back, a yieldable contact pin mounted in said panel, and a lead extending from said contact pin to said light.

2. A holding frame comprising a base plate, a clamp adapted to be secured to the steering column of an automobile, a blade secured to said base plate, and pivoted to the upper end of said clamp, and means on the clamp to hold the blade in adjusted position, a back pivoted to the rear edge of said base plate, a cover panel hinged to said back, screws extending through said cover into the back, and means whereby said back is adjustably connected to said plate.

3. A holding frame comprising a base plate, a clamp adapted to be secured to the steering column of an automobile, a blade secured to said base plate, and pivoted to the upper end of said clamp, and means on the clamp to hold the blade in adjusted position, a back pivoted to the rear edge of said base plate, a cover panel hinged to said back means whereby said back is adjustably connected to said plate, screws extending through said cover panel into the back, a reflector mounted on said cover panel, a light mounted in said reflector, an electrical contact block in said back, a yieldable contact pin mounted in said panel, and a lead extending from said contact pin to said light.

4. A holding frame comprising a base

plate, a clamp adapted to be secured to the steering column of an automobile, a blade secured to said base plate, and pivoted to the upper end of said clamp, said blade having 5 a slot formed therein, a bolt extending through said clamp and through said slot, a back pivoted to the forward end of the base plate, a cover panel hinged to said back, brackets pivoted to the back, and set screws 10 in the base plate adapted to engage said brackets.

5. A holding frame comprising a clamp, a base plate adjustably secured thereto, a back hinged to said base plate, a cover panel 15 superimposed on said back, a lamp mounted on said cover panel, and means for conduct-

ing a current of electricity to said lamp, said means comprising a yielding contact pin mounted in said panel and adapted to contact with a contact block in said back. 20

6. In a device of the type described a frame back, a cover panel for securing maps and the like to said frame back, means for securing said back and panel together for holding maps of different thicknesses, a light 25 carried by said panel, a terminal carried by said back, and a spring pressed pin yielding held in contact with said terminal and being in electrical connection with said light.

In testimony whereof I affix my signature.

EDDIE ORANGE HIGDON.
